(57) **CLAIM**

The ornamental design for a base unit for anal irrigation and a controller, as shown and described.

DESCRIPTION

FIG. 1 is a perspective view of a combination base unit and controller for anal irrigation;

FIG. 2 is a front elevation view thereof;

FIG. 3 is a back elevation view thereof;

FIG. 4 is a top plan view thereof;

FIG. 5 is a bottom plan view thereof;

FIG. 6 is a left side elevation view thereof;

FIG. 7 is a right side elevation view thereof;

FIG. 8 is a perspective view of a combination base unit and controller for anal irrigation shown in collapsed configuration.

FIG. 9 is a front elevation view thereof;

FIG. 10 is a back elevation view thereof;

FIG. 11 is a top plan view thereof;

FIG. 12 is a bottom plan view thereof;

FIG. 13 is a left side elevation view thereof; and,

FIG. 14 is a right side elevation view thereof.

In FIGS. 1-4, 6-8, and 11 the broken line showing of the tube depicts portions of the combination base unit and controller for anal irrigation that form no part of the claimed design.

1 Claim, 12 Drawing Sheets
